UNITED STATES PATENT OFFICE

2,509,219

ORNAMENTAL ELECTRIC LIGHT FIXTURE

William T. C. Desmond, West Orange, and William J. Desmond, Harrison, N. J., assignors, by direct and mesne assignments, to Noma Electric Corporation, New York, N. Y., a corporation of New York

Application April 27, 1948, Serial No. 23,604

6 Claims. (Cl. 240—52.4)

1

The invention relates to an ornamental electric light fixture simulating a candle stick and a holder therefor.

The main object of the invention is to provide an ornamental electric light fixture in the form of a candle stick and a translucent holder therefor and which is provided with a neon lighting means for simulating the flame of the candle stick portion and with an electric light bulb which is adapted to illuminate the translucent holder portion.

A further object is to provide an ornamental electric light fixture provided with a neon light means for effecting the direct lighting for the fixture and which is electrically connected in parallel with an electric light bulb adapted to illuminate a translucent base portion of the fixture.

A further object is to provide a simple, inexpensive construction, of an ornamental electric light fixture which is adapted for use for decorative lighting purposes such as a lighting means for Christmas trees, dressing or other types of tables, shop windows, or merchandise display counters.

Additional objects of the invention will appear more fully from the description hereinafter set forth.

For a better understanding of the invention reference is made to the accompanying drawing forming part of the specification, and in which:

Figure 1 is a central vertical section through an ornamental electric light fixture constructed in accordance with the invention; and

Fig. 2 is a view in elevation of the fixture.

Although the drawing shows a particular form of construction embodying the features of the invention and designed for use as a Christmas tree light, it should be understood that various modifications in the design and construction shown may be made within the scope of the annexed claims without departing from the spirit thereof.

Referring to the drawing, the electric light fixture shown therein, comprises a cylindrical hollow member 1 which may be made of a suitable plastic material and designed to represent a candle stick. The lower end of the cylindrical member 1 is formed with an enlarged hollow cylindrical shaped base portion 2, also made of a plastic material, and which is centrally mounted on the

2

depressed portion of a disk shaped member 3, which forms a cover portion for a hollow oval shaped base supporting member 4. The base supporting member 4 and its cover member 3 are made of a suitable translucent plastic material and are designed and shaped to represent a holder for the candle stick member 1. A suitable handle such as the ring 5 may be secured to the exterior surface of the oval shaped base holder member 4.

10 Internally mounted within the upper end of the candle member 1, is a neon light means supporting member 6, made of an insulating material, and which is provided with holes therethrough adapted to receive the terminal wires 7 and 8 of a neon light means 9 which is shaped to simulate a candle flame.

The hollow enlarged base portion 2 of the candle member 1, has mounted therein an electric light bulb receptacle 14 having the electrical conducting threads 13 which are adapted to receive the screw threaded base 15 of an electric light bulb 16.

Mounted at the lower end of the hollow oval shaped base member 4, and projecting therefrom is an outer threaded terminal member 10, which 25 is adapted to be screwed into a suitable size electrical socket connected to an electrical supply source. The threaded terminal member 10 supports a central conducting member 11, which is insulated from the outer threaded portion of the terminal member by the insulation 12.

The ends of the terminal wires 7 and 8 of the neon light means 9, which extend through the holes in the supporting member 6, are soldered to the insulated electrical conducting wires 17 and 18 which extend downwardly within the hollow candle member 1 and have their lower ends soldered to the screw threaded electric light bulb receptacle 14 positioned within the hollow base portion 2 of said candle member. The wire 17 35 has a suitable resistor means 19 positioned therein and the lower end of said wire is soldered to the central conducting means 20 of the electric light bulb receptacle 14. The lower end of the wire 18 is soldered to the side wall of said electric light bulb receptacle 14.

Also soldered to the central conducting means 20 of the receptacle 14 is the upper end of an insulated electrical conducting wire 21, which extends downwardly within the hollow oval shaped translucent base member 4, and has its

lower end extending through a hole formed through the insulating material 12 of the threaded terminal 10 and is soldered to the conducting member 11. A second insulated wire 22 has its upper end soldered to the side wall of the electric light bulb receptacle 14 and extends downwardly within the base member 4 and has its lower end soldered to the outer conductor threads of the terminal member 10.

The hollow base member 4 may be provided with a series of ventilating holes such as are indicated by the numeral 23.

It will be seen that by reason of the construction above described, and by the arrangement of the electrical conducting wires which connect the neon light means to the electric light bulb receptacle 14, and the electrical conducting wires 21 and 22, which connect said receptacle 14 to the terminal member 10, the neon light means 9 and the receptacle 14, and its electric light bulb, will be electrically connected together in parallel and that the electric current passing through the terminal member 10 will effect the lighting up of the neon light means 9 and the bulb 16 inserted in the receptacle 14 and that said bulb 16 will effect the illumination of the translucent base member 2, and the neon light means 9 will provide a light at the upper end of the candle member 1 which will simulate a flame for said candle member.

It will also be readily apparent that the electric light fixture shown in the drawing may be used as a decorative light for a Christmas tree by inserting the screw threaded terminal member 10 thereof in the usual electric socket provided in a Christmas tree light cord. The lighting fixture may also be adapted for use as a decorative table lamp by screwing said threaded terminal member 10 in a socket provided in a suitable base support. The lighting fixture may also be used for other decorative lighting purposes by merely screwing the terminal member thereof in any suitable sized socket connected to an electrical supply source.

What is claimed is:

1. An electric light fixture comprising a hollow cylindrical member simulating a candle stick and having a hollow enlarged base, a translucent hollow support member for the candle stick and its enlarged base, and provided with a threaded electrical terminal member extending from the bottom portion thereof, said hollow cylindrical candle stick member having a neon light means mounted in its upper end and an electric light bulb receptacle with an electric light bulb therein mounted in its hollow enlarged base, said neon light means and said electric light bulb receptacle being electrically connected in parallel and with said threaded electrical terminal member.

2. An electric light fixture comprising a candle shaped tubular member having a hollow enlarged base, a translucent hollow base supporting member shaped to simulate a holder for the tubular candle shaped member and its enlarged base and having a threaded electrical terminal member mounted at the lower end thereof, said candle shaped tubular member being provided with a neon lighting means at its upper end to simulate the flame of a candle and with an electrical receptacle positioned in the hollow base portion thereof, an electric light bulb mounted in said receptacle and projecting downwardly into the hollow base supporting member, said neon lighting means and said electric light receptacle being electrically connected in parallel and with said threaded electrical terminal member.

3. An electric light fixture comprising a hollow cylindrical body simulating a candle and having an insulated supporting member mounted in the upper end thereof and an enlarged hollow base portion, a neon light means mounted in said insulated supporting member, an electric light bulb receptacle positioned within said hollow base portion and having an electric light bulb mounted therein, a hollow oval shaped base supporting member for said hollow cylindrical candle member and its enlarged base portion made of a translucent material and formed with a disk shaped top portion, a threaded electrical terminal means mounted in and extending outwardly from the bottom portion of said hollow base supporting member, and means for electrically connecting said neon light means and said electric light bulb receptacle in parallel and with said threaded electrical terminal means.

4. A portable electric light fixture having a hollow cylindrical shaped member simulating a candle stick, and having an enlarged hollow base, a neon light means simulating a flame for the candle stick mounted in the top end thereof, an electric light bulb receptacle positioned within the enlarged hollow base portion of said candle stick member, a hollow oval shaped translucent base member supporting the hollow candle stick member and its enlarged base and simulating a holder for the simulated candle stick, an electric light bulb mounted in said electric light bulb receptacle and projecting downwardly into the hollow oval shaped base member and adapted to illuminate the same, a screw threaded electrical terminal mounted so as to project from the bottom of said translucent base member, and electrical conducting means mounted within said hollow cylindrical shaped member and within said hollow translucent base member and connecting said neon light means and said electric light bulb receptacle in parallel with each other and to said screw threaded electrical terminal.

5. A portable electric light fixture comprising a candle shaped tubular member having an electric light bulb receptacle mounted in the base portion thereof and an insulated means mounted within the upper end thereof, a neon light means mounted in the upper end of said candle shaped tubular member having its terminal wires extending downwardly through said insulating means, a translucent hollow supporting means for said candle shaped tubular member having a screw threaded electrical terminal member projecting from the base portion thereof, an electric light bulb mounted in said electric light bulb receptacle and projecting downwardly into the hollow supporting means, electrical conducting means secured at one end to the terminal wires of said neon light means and at their other ends to said electric light bulb receptacle, and electrical conducting means connected at their upper ends to said receptacle and at their lower ends to said threaded electrical terminal means.

6. A lighting fixture comprising an upper cylindrical hollow member having a neon light means mounted in and extending from the upper end thereof and having an enlarged hollow base portion with an electric light bulb receiving receptacle mounted within the same, an electric light bulb mounted in said receptacle and projecting downwardly therefrom, a lower hollow supporting member for said upper cylindrical hollow body member and its enlarged hollow base portion and made of a translucent material, an outer threaded electrical terminal member

mounted in the base of said hollow supporting member and extending outwardly therefrom, electrical conducting means positioned within said upper hollow body member for electrically connecting in parallel said neon light means to said electric light bulb receiving receptacle, and electrical conducting means positioned within the lower hollow supporting member for electrically connecting said electric light bulb receptacle to said threaded electrical terminal member. 10
